(57) CLAIM

The ornamental design for a ceiling fan blade as shown and described.

DESCRIPTION

FIG. 1 is a top perspective view of a ceiling fan blade showing our new design in the environment of a ceiling fan.

FIG. 2 is a top perspective view of the ceiling fan blade of FIG. 1.

FIG. 3 is a bottom perspective view thereof.

FIG. 4 is a top view thereof.

FIG. 5 is a bottom view thereof.

FIG. 6 is a front view thereof;

FIG. 7 is a rear view thereof.

FIG. 8 is a right-side view thereof; and,

FIG. 9 is a left-side view thereof.

Portions of the ceiling fan, light kit, and blade are shown in broken lines and form no part of the claimed design.

1 Claim, 8 Drawing Sheets
